(57) **CLAIM**

The ornamental design for an electronic musical instrument, as shown and described herein.

DESCRIPTION

FIG. 1 is a right side elevational view of an electronic musical instrument, according to an embodiment of the present invention;

FIG. 2 is a top plan view of the electronic musical instrument of FIG. 1;

FIG. 3 is a bottom plan view of the electronic musical instrument of FIG. 1;

FIG. 4 is a front elevational view of the electronic musical instrument of FIG. 1, the back elevational view being a mirror image;

FIG. 5 is a top, rear, and right side perspective view of the electronic musical instrument of FIG. 1;

FIG. 6 is a top, front, and left side perspective view of the electronic musical instrument of FIG. 1; and,

FIG. 7 is a top, front, and right side partial perspective view of the electronic musical instrument of FIG. 1.

The broken lines showing a tube assembly extending from the right side of the instrument in the drawing views are included for the purpose of showing the environment of the electronic musical instrument and forms no part of the claimed design.

The broken lines shown on the top surface of the instrument in the drawing views are included for the purpose of showing the environment of the electronic musical instrument and forms no part of the claimed design.

The broken lines shown on the right side and bottom surface of the instrument in the drawing views are included for the purpose of showing the environment of the electronic musical instrument and forms no part of the claimed design.
